WALTER G. WEIDNER, OF READING, PENNSYLVANIA

SCREW HOIST

Application filed September 10, 1927. Serial No. 218,662.

The present invention relates to screw hoists and particularly to hoists adapted for application to motor trucks for raising the body of the truck and dumping the same.

5 Objects of the invention are to improve hoists of this character and to maintain an increase of efficiency thereof, while at the same time decreasing the weight.

Other objects are to provide a hoist which 10 may be made to operate more swiftly in its downward movement than in its hoisting movement.

Other objects are simplicity of construction, cheapness of manufacture, and ease of 15 operation.

Still other objects will appear from the following specification and will be set forth in the appended claim, and I do not wish to be limited in the scope of my invention except as I shall be limited by said claim.

In the drawings:

Figure 1 is a section taken longitudinally through the center of the hoist casing.

Figure 2 is a section on the line 2—2 of 25 Figure 1, showing the chain gear box and gear connections therein.

Figure 3 is a detail view showing one of the sprockets and its nut.

Figure 4 is a sectional view showing a 30 modification of the drive means for the screw operating nuts.

Figure 5 is a section at right angles to that shown in Figure 4, showing further the relationship of the gears shown in Figure 4.

35 Referring to the drawings in detail, 10 designates a housing comprised of a center top brace member 11 and a lower brace member 12 connected at their ends to end housings 13 containing the screw operating nuts. Se-

40 cured to the under side of the housing 10 is a gear box 14 having journals 15 and 16 formed therein to receive and support the drive shaft 17 on which is mounted for rotation therewith gears 18 and 19. A countershaft 20 also 45 extends through apertures in the gear box and is provided with journals 21 and 22, the upper end of said countershaft having a journaled support in the central brace 11, as at 23.

50 Within the gear box loosely mounted on

said countershaft are gears 24 and 25, said gears having clutch cleats 26 formed on their adjacent faces adapted to be connected with a clutch 27 having longitudinal movement relative to the shaft 20 but being prevented from having rotary movement relative thereto by a longitudinal spline 28 formed on the shaft and articulating with a corresponding groove 29 formed on the inner periphery of said clutch. The clutch may be moved along the shaft 20 to bring the faces thereof into cooperation with the clutch surfaces 26 on either of the gears 24 or 25 selectively. An idler 25' meshes with the gears 18 and 24 respectively as illustrated in Figure 2.

Secured to the shaft for rotating therewith and located within the housing 10 are sprocket wheels 30 and 31 which are in driving connection through sprocket chains 34 and 35, with sprockets 32 and 33 secured to screw operating nuts 36 and 37 journaled in the end housings 13 and provided with threaded bores 38 to fit and cooperate with the threaded hoist screws 39 and 40, the nuts being preferably of brass and the lower ends thereof resting on the sheaves 41 of the ball bearings 42 which facilitate the rotation thereof.

The end housings are provided at the upper ends of the nuts with end thrust collars 43 to prevent vertical movement of said nuts. The end housings are secured to the central brace connection by means of studs 44 extending through apertured ears 45 and through apertures in said brace connections. An idler 46 may be provided within the housing 10 and may be arranged for adjustment to take up any slack that may develop in the sprocket chains 34.

While I deem a sprocket chain connection between the countershaft and the screw operating nuts as preferable in that it makes the device much lighter and is more positive and sure in its operation, I may employ a train of gears 50, 51, 52, 53 and 54 connecting the countershaft 20 with one of the screw operating nuts 36 through gears 51, and with the other screw operating nut 37 through gears 51a and 52a. The nuts 36 and 37 are preferably rectangular in cross section, as

shown in Figure 4, and the sprockets 32 and 33 are provided with bores therethrough corresponding to the outer surfaces of the nuts, whereby relative turning of the sprocket and the nut is prevented.

5 In operation, when it is desired to use the above described device as a hoist, the same is connected horizontally upon the frame of the truck and the drive shaft 17 is preferably
10 connected to a power take off, not shown, through suitable gear or chain connection. The clutch 27 is then moved by means of the forked lever 47 pivotally attached to the clutch and pivoted at 48 in the side of the
15 gear box, the relationship of the gears in the gear box being such that when the clutch is connected for hoisting the movement will be much slower than when it is connected for lowering the body of the truck. I prefer a
20 relationship such that will lower the body at a speed about three times as great as that employed in raising the same. It will be understood that in an emergency the body may be raised by this mechanism by hand.

25 Having described my invention, what I claim is:

In a device of the character described, upper and lower spaced parallel brace members, end housings having spaced apertured lugs, 30 bolts passed through the brace members and lugs for holding the end housings associated with the brace members, a counter shaft journaled in said brace members, sprockets carried by said shaft, screw operating nuts 35 journaled in the end housings, sprockets thereon, endless chains trained over the sprockets of said screw operating nuts and over the sprockets on said shaft, a gear box secured to the lowermost brace member and receiving said shaft, gears loosely mounted 40 on the shaft and arranged in said gear box, a sliding clutch on the shaft and cooperating with said gears selectively, a second shaft journaled in the gear box in parallelism with 45 the first mentioned shaft, and gears on the second mentioned shaft, an idler meshing with one of the last mentioned and one of the aforementioned gears, each of said screw operating nuts having an internal threaded bore, and threaded shafts extending through 50 the bores for the purpose specified.

In testimony whereof I affix my signature.

WALTER G. WEIDNER.
